UNITED STATES PATENT OFFICE.

HERMAN RAU, OF HAMILTON BEACH, AND CHARLES E. CHAPPLE, OF BROOKLYN,
NEW YORK, ASSIGNORS TO DOEHLER DIE-CASTING CO., A CORPORATION OF NEW
YORK.

MOLD EJECTOR DEVICE.

Application filed October 16, 1923. Serial No. 668,807.

To all whom it may concern:

Be it known that we, HERMAN RAU and CHARLES E. CHAPPLE, citizens of the United States, and residents of Hamilton Beach, 5 county of Queens, and State of New York, and Brooklyn, county of Kings, and State of New York, respectively, have invented certain new and useful Improvements in Mold Ejector Devices, of which the following is a full, clear, and exact description.

While our invention is applicable to sand molds as used in foundries, it is of special utility in connection with the casting of molds of plastic composition, such as plaster 15 of Paris, from match plates or patterns according to the process of the patent to John Kralund, No. 1,335,509 issued March 30, 1920, and will be described in connection with that process. That process consists in 20 casting or otherwise forming a plurality of pattern units which are matched and assembled into one complete pattern called a match plate, and then with the aid of a flask or frame, as is usual with poured 25 molds, flowing plaster of Paris upon the match plate, the plaster casting thus made being used as the mold for the finished casting. This process is of utility, for instance, in making castings from metals having relatively high melting points, such as brass, 30 the mold being broken away or otherwise removed from the casting thus formed.

It will be appreciated that the lifting of these molds from the match plate or pattern is accompanied by a certain liability 35 of injury to the mold, due to its fragile composition, either as a result of unsteadiness of the hands in manual lifting or friction between the various faces of the mold and its pattern. Since it is impossible to 40 get underneath the mold to support it until after it has been lifted far enough away from the pattern or match plate, it frequently happens that the friction between pattern and mold at deep pockets will cause the 45 mold to collapse when it is ejected.

An object of our invention is to provide means for lifting the plaster mold and its flask with the required degree of steadiness 50 and at the same time supporting the mold at such points as is necessary until the fingers can get underneath to support it at these points. Another object is to coordinate with mold and flask lifting means,

other means for removing in advance of 55 the mold any overhanging part of the pattern or match plate which is used for casting an undercut in the mold in case the pattern has such a part.

In accordance with our invention we 60 equip the match plate with loose ejector pins which are dropped into holes drilled in the plate and supported therein with their inner ends flush with the surface of the pattern. Since these pins are independent of 65 the ejector plate, it is possible quickly and cheaply to equip any match plate so that its mold may be mechanically ejected, and to arrange the pins, for example at the bottom of deep pockets, so that the mold 70 will be supported at the necessary points, while it is being ejected. Furthermore by adopting pins of the proper length a removable overhanging part of the pattern 75 may be ejected in advance of the mold.

Our invention has other objects and advantages and includes other features of construction as will appear from the following description of one embodiment of our invention.

We will now describe the illustrated embodiment of our invention and will thereafter point out our invention in claims.

The drawing shows an elevation, partly in section, of one embodiment of our invention.

The illustrated device has a base 1 upon which is a frame consisting of an annular plate 2 and supporting posts 3 between which move an ejector plate 4 toward and 90 from the plate 2. The ejector plate is elevated and lowered through one or more racks 5 operated by a pinion or pinions 6.

Supported on the frame 2 is a match plate or pattern 7. This pattern is the positive 95 of the final casting, the plane portion of its face forming the parting line for the mold, and its raised portions forming the mold recesses. A flask or frame 8 rests upon the upper face of the pattern 7, and the plaster of Paris is flowed within this flask to form the mold 9.

In order to receive and support ejector pins 10, the pattern 7 has a plurality of holes drilled therethrough. In the form 105 shown these holes are slightly enlarged in diameter at their upper ends, and the pins are provided with heads adapted to fit snug-

ly in the enlarged portions of the holes and have their upper ends just flush with the surface of the pattern. As a general designation we refer to these holes as countersunk and to the pins as headed, and it will be understood that we do not use these terms in any limited sense, but intend them to cover any equivalent construction in which the holes and pins are so shaped that the pins are supported therein independently of the ejector plate.

The location of the ejector pins will depend upon the contour of the pattern. Certain of them will be disposed underneath the flask 8 and the others will be properly disposed within the boundaries of the flask so as to lift the mold and support it at the proper points. In the construction shown these points are where the mold is the thickest, that is, where there are relatively deep pockets in the pattern, and generally speaking, those are the points that will be selected for the ejector pins.

In the construction shown the pattern includes an overhanging part 7^a for the purpose of casting an undercut in the mold 9. Obviously the mold cannot be ejected until the overhanging part of the pattern has been removed. In the form shown the part 7^a is supported in a hole in the pattern, resting upon a shoulder provided for that purpose. The hole is continued through the pattern or match plate and an ejector pin 11 is disposed in this hole underneath the bottom of the part 7^a and has its lower end resting upon the ejector plate 4.

It will be understood that in assembling the match plate and the other parts of the device, the match plate is attached to the frame 2 by means of screws, clamps, or any other means of fastening. The relatively short ejector pins 10 may be dropped in the match plate either before or after it is secured on the frame 2. The ejector pin 11 is then dropped through its hole in the match plate and the part 7^a is set into the pattern. The flask 8 having then been placed upon the match plate, the mold may be poured. As the ejector plate 4 is raised, it is evident that the pin 11 will first eject the overhanging part 7^a of the pattern and that the ejector

plate will then engage the pins 10 and lift the mold and its frame.

It is obvious that various modifications may be made in the construction shown in the drawings and above particularly described within the principle and scope of our invention.

We claim:

1. A mold ejector device comprising an ejector plate and operating means therefor, a pattern supported above the ejector plate, and ejector pins supported in the pattern independently of the ejector plate.

2. A mold ejector device comprising an ejector plate and operating means therefor, a pattern supported above the ejector plate and having a plurality of countersunk holes therethrough, and a plurality of headed ejector pins supported by their heads in said countersunk holes in the pattern.

3. A mold ejector device comprising an ejector plate and operating means therefor, a pattern supported above the ejector plate having a plurality of countersunk holes therethrough and having an upwardly removable overhanging part for casting and undercut supported in one of the said holes, a relatively long ejector pin in the hole underneath the said removable part of the pattern, and a plurality of shorter ejector pins provided with heads and supported by their heads in the countersunk holes.

4. A pattern having a plurality of countersunk holes therein, and a plurality of loose headed ejector pins supported by their heads in said countersunk holes.

5. A mold ejector device comprising an ejector plate and operating means therefor, a pattern supported above the ejector plate and having a plurality of countersunk holes therethrough, a flask resting on the pattern over certain of the countersunk holes, and headed ejector pins supported by their heads in the countersunk holes underneath the flask and in certain of the other holes.

In witness whereof we hereunto subscribe our signatures.

HERMAN RAU.

CHARLES E. CHAPPLE.
